W. E. TRENT

PROCESS FOR TREATING CARBONACEOUS MATERIALS

Filed Sept. 27, 1924

Inventor
Walter E. Trent

By Charles M. Thomas

Attorney

UNITED STATES PATENT OFFICE.

WALTER EDWIN TRENT, OF WASHINGTON, DISTRICT OF COLUMBIA.

PROCESS FOR TREATING CARBONACEOUS MATERIALS.

Application filed September 27, 1924. Serial No. 740,384.

The invention relates to improvements in a process for treating mixtures of coal and oil, or quantities of coal alone, for the removal of the oils which are recovered and then used to liquefy coal particles or for the purpose of effecting a separation of non-carbonaceous matter from the carbonaceous content of coal in the manner as described in my Patent No. 1,420,164.

10 The present application is a continuation in part of my co-pending application, Serial No. 325,632, filed September 23, 1919.

In accordance with this invention oils and the like removed from comminuted coal may 15 be used for different purposes, but I have found that if the coils recovered in the distillation of the coal are mixed with the carbonized residue, a fuel consisting of carbonized particles placed in a flowing condition 20 by the recovered oils is highly efficient and capable of broad use and application owing to the fact that the carbonized particles are largely freed from their ash forming content. Experiments have demonstrated that 25 by first removing the oil products from the coal and in then thoroughly intermixing the recovered oils with the carbonaceous content of the coal a highly desirable flowing fuel may be produced.

30 It will be understood that in carrying out this invention I first preferably reduce coal to a very fine degree and while wet I mix this coal with oil to cause the oil to combine with the carbon content of the coal forming 35 a plastic amalgam excluding ash forming substances therefrom. It is this amalgam that I preferably subject to distillation to remove the oils.

The invention also contemplates the provision of a process wherein the oils extracted 40 from a fuel amalgam by distillation may be again used for the purpose of purifying additional quantities of coal, after which said coal is subjected to distillation and the oils 45 recovered. In other words, the invention aims to provide a process wherein the purification of coal may be carried on largely through oils removed from the purified coal.

In carrying out my invention I preferably 50 use an apparatus as disclosed in the accompanying drawings, in which the figure represents a transverse sectional view of the device.

55 Referring more particularly to the drawings wherein like reference characters indi-

cate corresponding parts, the numeral 1 designates a bin or receiver which is adapted to contain pulverized coal, or a mixture of coal and oil. If the mixture consists of coal and oil of a substantially plastic nature it is 60 preferably manufactured in accordance with my Patent No. 1,420,164. As disclosed in this patent I purify the coal by first reducing the coal to a fineness of say 200 meshes per inch, and while wet I add to the 65 coal a quantity of hydrocarbon oil representing from 15 to 30 per cent of the coal used by weight. I thoroughly agitate these 70 substances and have discovered that the oil and the carbon content of the coal combine, forming a plastic mass, excluding non-carbonaceous matter and water. Either this material or finely comminuted coal free of oil may be introduced to the bin 1. The 75 material thus introduced is fed by the conveyor 2 through a feed pipe 3 which is in communication with a gas, liquid, steam, oil or water pipe 4 having a pump 5 therein disposed within its line and communicating with any suitable source of supply. The 80 finely divided coal or the coal and oil mixture is fed from the conveyor 2 and carried in suspension in the rapidly moving gas or fluid current through the coil 6 disposed within a combustion chamber 7 which is 85 heated by heating gases from the burner 8 to the desired temperature. It will be seen that the heat is applied to the material passing through the pipe 6 internally and this heat is sufficient to vaporize the oil 90 mixed with the coal as well as the volatiles contained in the coil 6. The temperatures employed may vary, but I preferably only use a temperature sufficiently high to remove the oils in the materials undergoing treatment. 95 From the conducting pipe 6 the material leads to an outlet pipe 7 from where the gases and vapors pass off to a condenser 10, the condensable oils being collected in a receiver 11 while the incondensable gases go 100 off through a pipe 12 to a suitable point of collection. From the pipe 7 the carbonized residue is deposited into an enlarged receiver 13 where this residue is collected.

If the material undergoing treatment is 105 an agglomerated mass of coal and oil the carbonized residue collected in the receiver 13 will be largely free of ash. The low temperatures used in the retort prevent a material agglomeration of the fine coal particles 110

so they are collected as carbonized particles. These carbonized particles may be mixed with the oil collected in the receiver 11 so as to form a flowing mixture, which I have found highly useful for many purposes. That is to say, the oil removed from the coal is used with the carbonized particles to produce a flowing substance and if sufficient oil is not removed from the coal for this purpose additional oil from an extraneous source can be used.

Another important feature of this invention resides in the fact that when an agglomerated mass of coal and oil is being treated the oil is recovered by distillation and the contained oil of the coal is likewise removed. This oil is collected in the receiver 11, and as before stated the oil thus collected can be again returned to the agitating vessel and then used as a treating agent for the purpose of treating additional quantities of raw coal. This operation is highly desirable in localities where hydrocarbon oil is not obtainable and it is beneficial to utilize largely the contained oil of a charge of coal for the purification and treatment of a fresh supply of unclean coal. In this event the carbonized particles are collected and used as a fuel either in their ordinary form or as briquettes or otherwise. In distilling the materials I preferably employ a temperature of say 600° F., which is sufficiently high to remove the lighter oil fractions without coking the carbonized particles. Instead of forcing the mixture through the pipe 6 in the retort under pressure or while in a moving current of inert gas, water, steam, oil, or the like, I can, if desirable, directly carry this material through a retort on an endless conveyor, where the same is discharged at one end of the conveyor into a suitable hopper, while the vapors pass off to a condenser and are collected. It will furthermore be understood that many other types of apparatus can be used for carrying out this process and that the apparatus disclosed has merely been shown for the purpose of illustrating one type of apparatus that I have successfully used.

Having thus described my invention, what I claim is:

1. A process of producing a fuel, consisting in distilling oils and in removing ash forming substances from the carbonaceous content of coal, and in then mixing the oil so produced with the carbonaceous residue to place the same in a wet condition.

2. The method of producing a liquefied carbonaceous fuel, which comprises subjecting coal in a finely pulverized state to the action of heat to distill oils therefrom without fusing the carbonaceous particles together, and in mixing the oils so produced with the carbonaceous fuel particles.

3. A method of producing a wet carbonaceous fuel, which consists in subjecting finely pulverized coal to the action of heat to distill the oils from the coal, and in then mixing the oil so produced with the carbonaceous particles, and in agitating the same to form an amalgamated substance of oil and carbon particles.

4. The method of producing a composite carbonaceous fuel, consisting in distilling finely pulverized coal to remove oils therefrom, and in then agitating the oils so produced with the carbon-fuel to form an agglomerated mass of the comminuted carbonaceous material and the oil.

5. A method of treating carbonaceous fuels, consisting in purifying coal by mixing the same in a finely divided condition while wet with a hydrocarbon agent, in agitating the same to cause the carbon content of the coal and the oil to combine forming a plastic agglomerate, in passing said agglomerate through a heating zone to remove oil therefrom by distillation, and in mixing said removed oils with a fresh charge of comminuted coal for purifying the same.

6. A method of treating carbonaceous fuels, consisting in mixing comminuted coal and oil, in passing said mixture to a heating zone to recover the oils by distillation, in mixing the recovered oils with comminuted coal particles.

In testimony whereof I amx my signature.
WALTER EDWIN TRENT.
